UNITED STATES PATENT OFFICE.

SAMUEL EMERY CREECH AND PERRY BLAND, OF SULLIVAN, ILLINOIS.

DESIGN FOR A HAIRPIN.

53,872.

Specification for Design. Patented Sept. 16, 1919.

Application filed May 13, 1919. Serial No. 296,833. Term of patent 14 years.

To all whom it may concern:

Be it known that we, SAMUEL E. CREECH and PERRY BLAND, citizens of the United States, and residents of Sullivan, in the county of Moultrie and State of Illinois, have invented a new, original, and ornamental Design for Hairpins, of which the following is a specification, reference being had to the accompanying drawing, forming part thereof.

The figure is an enlarged plan view of the hair pin.

We claim:

The ornamental design for a hairpin, as shown.

Signed at Sullivan, in the county of Moultrie, and State of Illinois, this 7 day of May, 1919.

SAMUEL EMERY CREECH.
PERRY BLAND.
